UNITED STATES PATENT OFFICE.

HARRY W. BELL, OF NEW YORK, N. Y.

LINTEL-BLOCK.

SPECIFICATION forming part of Letters Patent No. 685,318, dated October 29, 1901.

Application filed April 18, 1901. Serial No. 56,381. (No model.)

To all whom it may concern:

Be it known that I, HARRY W. BELL, a citizen of the United States, residing in the borough of Manhattan, in the county of New York and State of New York, have invented certain new and useful Improvements in Lintel-Blocks, of which the following is a specification.

This invention relates to building construction, particularly floors and ceilings, and especially to lintel-blocks, and has for its object to provide a fireproof floor which shall at the same time be proof against the entrance of rats, mice, or vermin of any kind and unusually firm, strong, and durable, though light and inexpensive on account of the economical employment and distribution of the material thereof.

A further object is to provide a flooring for buildings which may be simply and rapidly constructed and also shall combine the foregoing advantages.

A further object is to provide an improved lintel-block comprising an interdependent core and reinforcing means enveloped in a plastic material.

This invention comprises in a general way a plurality of parts comprehending a core, a hanger resting on said core, reinforcing means suspended by said hanger, and stiffening means supported on said reinforcing means, the whole enveloped in and surrounded by a plastic material; but one or more of the component parts may be omitted without affecting the invention. One form, and, if desired, it may be the preferred form, of the invention is illustrated in the drawings accompanying and forming part of this specification, in which—

Figure 1 is a side elevation of the improved lintel-block, the reinforcing means shown in dotted lines and the I-beams shown in section. Fig. 2 is a transverse sectional view of the improved lintel-block with a floor-block in position, said floor-block being partly broken away. Fig. 3 is a perspective view of the reinforcing means of said improved lintel-block. Fig. 4 is a perspective view of another form of such reinforcing means. Fig. 5 is a detailed view of a hanger in perspective. Fig. 6 is a transverse sectional view of the modified form of block.

As shown in the drawings, the improved lintel-block A comprises a core 3, formed of a sheet of metal set on edge and extending longitudinally through the center of the lintel-block A, said core having its upper and lower edges turned back on itself, if desired, and provided at intervals, if desired, with anchors b, comprising pieces of metal passing through such sheet and extending horizontally out from each side. Resting on the upper edge of said core 3 at intervals and extending downward on each side of said core 3 are metallic V-shaped hangers C, having their lower ends curved outward and upward, forming hooks c. These hangers C may, if desired, be formed of a continuous sheet of metal. Extending lengthwise said lintel-block A and supported in the hooks c is a metallic member D, comprising one or more rods. Extending crosswise of said block A and resting on the members D are metal strips E. Instead of the strips E a sheet of metal may be used, proper recesses being cut out to receive the hangers C. Enveloping and surrounding the parts organized as described is a plastic material F, molded into shape and having inclined sides, which may be provided, if desired, with shoulders a, which extend over the hooks c.

From the construction described it is evident that the smallest possible sections of metallic materials may be used for the core, hangers, rods, and strips, since the material which surrounds the metallic structure stiffens these members and enables very small sections to withstand relatively great stresses and overcome any tendency to buckle. The construction also has the advantage of protecting the metal parts from oxidation and destruction by heat. The metal gives the lintel-block great strength in resisting shearing and tensional stresses, and the peculiar construction by which the turned-up lower ends of hangers C extend out under the shoulders a reinforces such shoulders a and prevents the plastic material F from being crushed or disintegrated by whatever pressure is placed upon them. Moreover, by reason of the inclined sides of the lintel-block A the strain is not directly vertical, but is an indirect vertical and transverse pressure.

I do not limit myself to the particular struc-

ture described herein; but the same may be varied in its details and combination of parts without departing from the principle and spirit of the invention.

5 Having described the invention, I claim—

1. An improved lintel-block having a metallic core with one or more of its edges turned upon itself and one or more anchors extending through such core and projecting from 10 the side.

2. An improved lintel-block having a sheet-metal core and a reinforcing member comprising a hanger resting on the upper edge of said core and extending downward therefrom 15 and formed of a plurality of parts.

3. An improved lintel-block having a sheet-metal core and a reinforcing member comprising a hanger resting on the upper edge of said core and extending downward there- 20 from.

4. An improved lintel-block having a sheet-metal core and a plurality of reinforcing members comprising rods extending lengthwise said block, one on each side of said core and 25 connected therewith.

5. An improved lintel-block having a sheet-metal core and a reinforcing member comprising a strip extending crosswise said block below said core.

30 6. An improved lintel-block having a core and a plurality of reinforcing members comprising an anchor extending through said core and a hanger resting on the upper edge of said core and extending downward on each 35 side thereof.

7. An improved lintel-block having a core and a plurality of reinforcing members comprising a hanger resting on the upper edge of said core and extending downward on each 40 side thereof and having its lower ends turned up; and rods supported in said upturned ends.

8. An improved lintel-block having a core and a plurality of reinforcing members comprising a hanger resting on the upper edge of 45 said core and extending downward on each side thereof; rods supported by the lower parts of said hanger; and a crosswise member supported by said rods below said core.

9. An improved lintel-block having a core 50 and a plurality of reinforcing members, such members comprising anchors extending through said core and projecting from each side thereof; a hanger resting upon the upper edge of said core and extending diagonally downward from each side thereof, said hanger having its lower ends turned up; rods supported in said upturned ends; and strips extending crosswise said block and resting on said rods.

60 10. An improved lintel-block having a core and a plurality of reinforcing members, such members comprising a hanger resting on the upper edge of said core and extending downward on each side thereof; and rods support- 65 ed by such hanger.

11. An improved lintel-block having a core

and a plurality of reinforcing members, such members comprising a hanger resting on the upper edge of said core and extending downward on each side thereof; and a strip ex- 70 tends crosswise said block below said core.

12. An improved lintel-block having a core and a plurality of reinforcing members, such members comprising a hanger resting on the upper edge of said core and extending downward 75 on each side thereof; rods supported by said hanger; and a strip extending crosswise said block below said core and resting on said rods.

13. An improved lintel-block having a core 80 and a plurality of reinforcing members, such members comprising rods on each side said core near the bottom of said block; and crosswise strips resting on said rods.

14. An improved lintel-block comprising a 85 core comprehending a plurality of reinforcing members, such members comprising anchors extending through such core; a hanger resting on the upper edge of said core and extending downward from each side thereof; 90 and crosswise strips below said core; all such members enveloped in and surrounded by a plastic material having inclined sides with shoulders formed therein.

15. An improved lintel-block comprising a 95 core and a plurality of reinforcing members, such members comprising a hanger resting on the upper edge of said core and extending downward, and a plastic material enveloping and surrounding such members and 100 having inclined sides with shoulders formed therein.

16. An improved lintel-block comprising a core and a plurality of reinforcing members, such members comprising a hanger resting 105 on the upper edge of said core and extending downward; rods supported by said hanger; and a plastic material enveloping and surrounding such members and having inclined sides with shoulders formed therein. 110

17. An improved lintel-block comprising a core and a plurality of reinforcing members, such members comprising a hanger resting on the upper edge of said core and extending downward; rods supported by said hanger; 115 a crosswise strip resting on said rods; and a plastic material enveloping and surrounding such members and having inclined sides with shoulders formed therein.

18. An improved lintel-block comprising a 120 core and a plurality of reinforcing members, such members comprising a hanger resting on the upper edge of said core and extending downward, said hanger having its lower ends turned up; and a plastic material enveloping 125 and surrounding such members and having its sides inclined and shoulders formed therein over such upturned ends.

19. An improved lintel-block comprising a core and a plurality of reinforcing members, 130 such members comprising anchors extending through such core; a hanger resting on the

upper edge of said core and extending downward therefrom; and a plastic material enveloping and surrounding such members and having inclined sides with shoulders formed 5 therein.

20. An improved lintel-block comprising a core and a plurality of reinforcing members, such members comprising anchors extending through such core; a hanger resting on the 10 upper edge of said core and extending downward therefrom, said hanger having its lower ends upturned; rods supported by said upturned ends; and a plastic material enveloping and surrounding such members and 15 having inclined sides with shoulders formed therein over said upturned ends.

21. An improved flooring comprising lintel-blocks each comprehending a core and a plurality of reinforcing members, such members 20 comprising anchors extending through said core; a hanger resting on the upper edge of said core and extending downward; rods supported by said hanger; and a plastic material enveloping and surrounding such members 25

and having its sides inclined with shoulders 25 therein extending over said rods.

22. An improved flooring comprising lintel-blocks each comprehending a core and a plurality of reinforcing members, such members comprising a hanger resting on the upper 30 edge of said core and extending downward; rods supported by said hanger; and a plastic material enveloping and surrounding such members and having its sides inclined with shoulders therein extending over said rods. 35

23. An improved flooring comprising lintel-blocks each comprehending a core and a plurality of reinforcing members, such members comprising anchors extending through said core; a hanger resting on the upper edge of 40 said core and extending downward; rods supported by said hanger; and a plastic material enveloping and surrounding such members and having inclined sides.
